TOY PARROT

Hisashi Suzuki, Tokyo, Japan, assignor to Louis Marx & Co. Inc., New York, N.Y., a corporation of New York

Filed Mar. 15, 1963, Ser. No. 73,978

Term of patent 3½ years

(Cl. D34—2)

FIG. 1.

FIG. 2.

FIG. 1 is a front perspective view of a toy parrot showing my new design; and

FIG. 2 is a side elevational view thereof.

I claim:

The ornamental design for a toy parrot, as shown.
